UNITED STATES PATENT OFFICE

2,269,611

DROPOUT CIRCUIT INTERRUPTER

Joseph S. Thompson, Los Altos, Calif., assignor
to Pacific Electric Manufacturing Corporation,
San Francisco, Calif., a corporation of California

Application January 13, 1941, Serial No. 374,151

9 Claims. (Cl. 200—114)

The present invention relates to high voltage circuit interrupters, and more particularly to a fusible circuit interrupter of the drop out type which, as is well understood, becomes disengaged from an upper contact and rotates into a suspended position from a lower contact where it remains until replaced.

An object of the invention is to provide an improved means by which dropout circuit interrupters of the above type may be replaced in a simple and convenient manner by means of a stick provided for this purpose.

Another object of the invention is to provide an improvement in dropout fusible circuit interrupters of the trunnion supported type which, in addition to facilitating a replacing of the interrupter upon its supporting contacts, will also operate to prevent an accidental displacement of the interrupter from its trunnion engaging support during the final replacing operation.

A further object of the invention is to provide a novel means by which dropout fuse units of the trunnion supported type may be conveniently placed upon their trunnion engaging support in a simple and convenient manner and which will operate, when the dropout fuse unit is moved into its final operative position, to provide a good contact making engagement between the trunnions of the dropout fuse unit and the trunnion engaging terminal support.

Other objects and advantages of the invention will be in part evident to those skilled in the art and in part pointed out hereinafter in connection with the accompanying drawing, wherein there is shown by way of illustration and not of limitation several embodiments thereof.

In the drawing, wherein like numerals refer to like parts throughout the several views;

Figure 1 is a side elevation of a fusible dropout circuit interrupter embodying the present invention.

Figure 2 is an enlarged fragmentary view showing details of the invention as applied to the dropout unit of Figure 1.

Figures 3 and 4 are views similar to Figure 2 showing modified forms of the invention, and

Figures 5, 6 and 7 are detailed fragmentary views showing modified forms of an element of the invention.

For the purpose of illustrating the present invention there is shown in Figure 1 of the drawing a fusible dropout circuit interrupter of the type illustrated and described in my copending application Serial No. 320,807, filed February 26, 53

1940, and entitled Fusible circuit interrupter. As here shown, the fusible circuit interrupter, designated by the numeral 10, is adapted to be placed between suitable high voltage line terminals 11 and 12 that are carried by an insulator 13 which is adapted to be mounted upon a cross-arm or other suitable support 14 by means of a bracket 15. At its lower end the fusible dropout unit 10 is provided with a terminal or contact forming end 16 which has oppositely extending trunnions 17 that are adapted to be cradled in recesses 18 formed in two spaced and extending portions 19 adjacent the lower line terminal contact 11. At its other end the fusible dropout unit 10 is shown as having a latching contact 20, the details of which form the subject matter of my aforesaid copending application. When the fusible dropout unit 10 is in its operating position, the latching contact 20 will be held in contact making engagement with the line terminal 12 and thus a circuit will be established through the fusible dropout unit 10 between the line terminals 11 and 12.

These dropout circuit interrupters are primarily intended for use on high voltage circuits and they are, therefore, generally mounted in an elevated position upon a pole or tower where replacement is difficult unless some special means is provided for this purpose. In the past, for replacing dropout fuse units of the trunnion supported type, it has been customary to provide a long insulating pole having a clamping jaw at its end in which the body of the fuse is held while being placed in an operative position by a lineman at a safe distance therefrom. Another expedient has been to provide one or the other of the fuse terminals with an integral or rigidly formed eyelet into which an extension upon a suitable insulated pole may be placed to thus install the dropout unit. This latter expedient has found considerable favor because of its simplicity and inexpensive character, but it has been found that in some instances the provision of such an integrally formed eyelet upon the terminal end of the fusible dropout unit is not practical.

As is illustrated in Figure 1 of the drawing, the above difficulties have been overcome in the present invention by providing the lower or trunnion carrying end of the fusible dropout unit 10 with a bail 21 that is adapted to be engaged by an extending finger 22 carried by an insulating pole 23 in such a manner that the dropout unit 10 will be held in a suspended position where its

trunnions 17 can be conveniently dropped into the cradle forming recesses 18 of the extending portions 19 adjacent the lower terminal contact 11. After the fusible dropout unit 10 is thus positioned in the cradle forming recesses 18, the bail 21 is permitted to drop free of the extending finger 22 where it will not interfere with a subsequent rotation of the dropout unit 10 into its final operative position by a rotating force subsequently applied to the body of the fuse unit through the pole 23, as is indicated by dot and dash lines in this figure of the drawing.

As is more clearly shown in Figure 2 of the drawing, the trunnions 17 upon the contact forming end 16 of the fusible dropout unit 10 are flattened or cut away on opposite sides in lines parallel to the axis of the fusible dropout unit 10, and the cradle forming recesses 18 are provided with an overhanging lip 24 so that a displacement of the trunnions 17 from the cradle forming recesses 18 is prevented when the dropout unit 10 is rotated into its final operative position with respect to the upper line terminal 12 by means of the pole 23, as previously described.

In Figure 3 of the drawing there is shown an arrangement wherein the provision of the overhanging lip 24 upon the cradle forming recesses 18 and the flattening of the trunnions 17, as above described, is avoided. In this arrangement the bail 21 performs the additional function of preventing a displacement of the dropout fuse unit 10 from the cradle forming recesses 18. As here shown, the trunnions, designated by the numeral 25, are cylindrical in outline and the bail 21, when released after an initial placing of the trunnions 25 in the cradle forming recesses 18, takes a position of rest upon the cradle carrying extensions 19 in cooperating relation with an abutment 26 that may be formed in any suitable manner upon one or both of the extending portions 19 of the lower terminal 11. With such an abutment 26, it will be seen that due to the inclined character of the cradle forming recesses 18 and the location of the abutment 26 substantially opposite thereto, the bail 21 will, when released, operate to prevent any displacement of the trunnions 25 from the recesses 18 during a subsequent rotative movement of the dropout fuse unit 10 into its final operative position by means of its placing stick.

In Figure 4 of the drawing there is shown a further variation of the invention in which a bail 21 of spring material, in addition to providing the above described functions, may also be relied upon to establish a good electrical contact between the trunnions 25 of the dropout fuse unit 10 and the extending portions 19 which carry the cradle forming recesses 18. In this latter arrangement, instead of the upwardly extending abutment 26, the extending portions 19 are shown as provided with suitably arranged notches 27 into which the outermost portion of the bail 21 is adapted to finally come to rest. The bail 21 is also here shown as secured in a position slightly eccentric to the axis of the extending trunnions 25. With this arrangement it will be seen that when the bail 21 is secured eccentric to the trunnions 25 in the manner illustrated, it will be placed under compression when the trunnions 25 of the fusible dropout unit 10 are rotated counter-clockwise in the cradle forming recesses 18 and, as a result of its springing character, the bail 21 will exert a yielding pressure upon the trunnions 25 which will establish 75

a good electrical contact between the trunnions 25 and the extending portions 19.

As shown in Figures 5, 6 and 7 of the drawing, the bail and its mode of attachment to the trunnions 17 of the fusible dropout unit 10 may take many forms. The arrangement illustrated in Figure 5 is considered to be the simplest and most inexpensive, as it only requires that the trunnions be provided with a bail receiving recess at their ends, either concentric or eccentric to their axes, into which inwardly bent ends of the bail 21 may be disposed. In Figure 6 there is shown a different form of bail 28 that may be stamped from sheet metal so as to provide eyelets 29 at the ends thereof which may be snapped over the trunnions 17 of the dropout fuse unit 10, and in Figure 7 of the drawing there is shown a bail 30 having a substantially square configuration with eyelets 31 formed at its ends that are adapted to be disposed over concentric or eccentrically arranged extensions 32 provided at the ends of the trunnions 17 of the dropout fuse unit 10.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described my invention, what I claim and desire to secure by Letters Patent is:

1. The improvement in a cradle and trunnion supported fusible dropout circuit interrupting unit, which comprises the provision of a placing stick engaging bail pivotally secured at its ends to the trunnioned end of the dropout unit.
2. The improvement in a cradle and trunnion supported fusible dropout circuit interrupting unit, which comprises the provision of a placing stick engaging bail at the cradle supported end of the dropout unit, said bail being pivotally secured at its ends to the trunnions carried by the dropout unit.
3. In a dropout fuse unit of the character described, the combination of a cradle forming member, a fuse unit having oppositely extending trunnions adapted to engage said cradle forming member and form a pivotal support for said fuse unit, and a bail pivotally secured at its ends to said oppositely extending trunnions by which said fuse unit may be placed upon said supporting member while suspended from a fuse unit replacing stick.
4. In a dropout fuse unit of the character described, the combination of a support having spaced cradle forming portions, a fuse unit having oppositely extending trunnions engageable with said spaced cradle forming portions to form a pivotal support for said fuse unit, a bail pivotally secured at its ends to said oppositely extending trunnions by which said fuse unit may be placed upon said supporting member while suspended from a replacing stick, and means upon said support engageable by said bail to prevent a displacement of said trunnions from said cradle forming portions when the fuse unit is in its operative position.
5. In a dropout fuse unit of the character described, the combination of a support having

open cradle forming recesses, a fuse unit having oppositely extending trunnions adapted to drop into said cradle forming recesses and form a pivotal support for said fuse unit, a bail pivotally secured at its ends to said oppositely extending trunnions by which said fuse unit may be placed upon said supporting member while suspended thereby from a replacing stick, and an abutment upon said support disposed adjacent to said open cradle forming recesses and engageable by said bail for preventing a displacement of said trunnions from said open cradle forming recesses as the fuse unit is subsequently pivoted into its normal operating position by said placing stick.

6. In a dropout fuse unit of the character described, the combination of a support having diagonally disposed open cradle forming recesses, a dropout fuse unit having oppositely extending trunnions adapted to drop into said cradle forming recesses and form a pivotal support at the lower end of said fuse unit, a bail pivotally secured at its ends slightly eccentric to the axis of said oppositely extending trunnions, and an abutment upon said support disposed in opposed relation to said cradle forming recesses and engageable by said bail as said fuse unit is moved

10 into its normal operating position, whereby said trunnions will be biased into contact making engagement with the recesses of said support as the fuse unit is rotated into its operative position.

5 7. A dropout fuse unit having cradle engaging trunnions extending from its lower terminal forming end, said trunnions having recesses formed in their outer ends, and a bail secured to said trunnions by bent ends disposed in the recesses of said trunnions.

15 8. A dropout fuse unit having cradle engaging trunnions extending from its lower terminal forming end, said trunnions having eccentrically disposed recesses formed in their outer ends, and a bail secured eccentric to said trunnions by having its ends extended into the recesses of said trunnions.

20 9. A dropout fuse unit having cradle engaging trunnions extending from its lower terminal, said trunnions having reduced and projecting extensions, and a bail secured to said trunnions by eyelets formed at its ends and bent around the reduced and projecting extensions of said trunnions.
